UNITED STATES PATENT OFFICE.

CARL GUGGENBUEHLER, OF NEWARK, NEW JERSEY.

UNIVERSAL LUBRICATING DEVICE.

Application filed January 29, 1921. Serial No. 440,840.

To all whom it may concern:

Be it known that I, CARL GUGGENBUEHLER, a citizen of Germany, residing at Newark, in the county of Essex and State of New Jersey, have invented certain new and useful Improvements in Universal Lubricating Devices, of which the following is a specification.

The present invention relates to lubricating devices, and constitutes an improvement of the invention described and shown in my co-pending application Serial #348,313, filed December 30th, 1919, and of which the present application is a continuation.

15 The object of the invention is to so construct the lubricating device that both the discharge controlling valve and the lubricant feed will be automatically controlled from a common means controlling the operation of the vehicle.

20 Another object of this invention is to provide a positively operated lubricant feeding means which will be automatically operated at aforedetermined times, but not continuously, whereby waste of lubricating material will be obviated.

25 My invention will be fully understood by reference to the accompanying drawing in which similar characters denote corresponding parts and in which Fig. 1 is a side elevation of my device shown as applied to a motor vehicle; Fig. 2 is an enlarged vertical section of the device proper on line 2-2 of Fig. 1. Fig. 3 is a reduced top plan view of 30 the device and Fig. 4 a reduced cross section on line 4-4 of Fig. 2.

35 10 denotes the vehicle of which 11 is the motor casing and 12 the means for controlling the operation of the vehicle, such as 40 emergency brake controlling lever. The lubricating device L may be arranged at a suitable place within the casing 11 and may comprise a double container 13, 14 for grease and oil or the like.

45 As the present improvement merely deals with the construction of the plunger working in the central container 13 and the mode of feeding said plunger while operating the valve controlling the discharge openings of 50 said central container, it will be unnecessary to describe the details of or refer hereafter to the second container 14 and the individual valves controlling the discharge openings of the latter. Moreover, the device is not limited to double containers, but may be con-

structed with one cylinder to contain only one kind of lubricant.

The bottom of this container 13 is closed by a cap shaped bottom 15 having a plurality of discharge openings 16 which are controlled by a rotary valve 17 mounted in said bottom substantially as in the aforesigned co-pending application, and having openings 18 which are arranged, sized and spaced in conformity with the openings 16.

60 Arranged in the container 13 is a longitudinally movable plunger 19 for feeding the lubricant. This plunger is guided so that it will not be capable of turning and to this end it may be provided with diametrically opposed projections 20 engaging longitudinal guide grooves 13' formed in the inner wall of the container 13. The stem or rod 21 of said plunger is adapted to extend through a central opening 22 provided in 65 the top 23 of the container. Said rod is provided with a central bore 21' extending longitudinally throughout the length thereof and serving as charge opening for the grease or other lubricant.

70 80 This charge opening is normally closed by a plug 25 extending through the said bore and screwing with its lower threaded end 25' in the lower threaded part of the bore 21'.

85 The outer circumference of the stem is provided with fine thread 21² and adapted to work in a correspondingly threaded nut 26 mounted in the central opening 22 of the top 23, to be capable of rotary but not longitudinal movement. Fixed to or formed integrally with the nut 26 is a ratchet wheel 27 whereby intermittent rotary motion can be imparted to said nut, by the rotation of which the plunger 19 through its stem 21 will be moved to feed the lubricant.

90 Co-operating with said ratchet wheel is a spring actuated pawl 28 pivoted at 28' in an arm 29 which is fulcrumed at 29' to the top 23 of the container.

95 100 This arm 29 extends parallel to the arm 30 fixed to and projecting from the valve 17 and is operatively connected thereto by a vertical rod 31.

105 The member 12 which in the present example is shown as brake operating lever, but which may be any other means for controlling the operation of the vehicle, has connected to it a bar 32 to which is pivoted one end of a double armed lever 33 fulcrumed at 34 to a stationary part 35 of the vehicle. The 110

other end of said lever is pivoted to a link 36 engaging the outer end of the arm 30.

As it is desired that the valve 17 be operated somewhat in advance of the plunger, 5 the arm 29 is formed at its outer end with a loop 29² in which the upper end of the vertical rod 31 is movably engaged. This loop provides enough play to permit the operation of the valve to precede that of the 10 plunger.

The mode of operation of my device is as follows:

Whenever it is desired to feed the lubricant to different parts of the machine, either 15 when the machine is started and the emergency released or some other member controlling the operation of the machine is operated, the particular member such as the lever 12 when moved transmits movement 20 to the valve 17 through the medium of the arm 32, lever 33 and link 36. Simultaneously, the rod 31 is moved in circular direction with the arm 32, and the upper end of 25 said rod slides from one end of the loop 29² towards the opposite end and when reaching the latter carries the arm 29 along with it. The arm 29 receives thereby a rotary motion 30 around its fulcrum 29' as a result of which its pawl 28 will turn the nut 26 through the medium of the ratchet 27 and cause the plunger 19 to slightly move inwardly feeding the lubricant through the opened discharge 35 openings.

The nut 26 may be provided with means 40 for its operation by hand, so as to permit the turning of the nut in opposite direction and thereby move the plunger back to its initial position after the contents of the 45 container have been used up and the latter is to be refilled. Such means may consist of thumb members 37 or the like.

The plug 25 may have its outer end formed to a square 25' or other suitable means for

engagement of a proper tool whereby it may be readily manipulated.

It is obvious that the device can be variously modified without departing from the principle of my invention and I, therefore, do not wish to limit myself to the details shown and described.

What I claim and desire to secure by Letters Patent is:

1. In an automatic lubricating device for motor vehicles, the combination with means for controlling the operation of the vehicle, 55 of a lubricant container having discharge openings, a valve for controlling said discharge openings, a plunger for feeding the lubricant, said plunger having a threaded stem, a nut for said stem held against longitudinal movement, a ratchet wheel connected to said nut, a pawl co-operating with said ratchet wheel and common means for operating said valve and pawl to open said discharge openings in advance of the feeding 60 of the lubricant, said means being controlled from the first named means.

2. In an automatic lubricating device for motor vehicles, the combination with means for controlling the operation of the vehicle, 70 of a lubricant container, a discharge valve therefor, a longitudinally guided plunger in said container having a threaded stem, a nut for said stem rotatively borne on said container, a pawl co-operating with said 75 nut, an arm carrying said pawl and operatively connected to said valve and arm, said means being controlled from said first named means.

In testimony whereof I affix my signature in presence of two witnesses.

CARL GUGGENBUEHLER.
